ABSTRACT OF THE DISCLOSURE

An endless sieve for paper-making machines which sieve is woven from synthetic filaments, the connections between the ends of the individual warp filaments being distributed over a large area of the web and the warp filaments being connected together at their end face pointing in the filament direction independently of the weft filaments, i.e. in laterally movable relation to the weft filaments.

This invention relates to woven structures such as screens or sieves made from synthetic filaments, and particularly to so-called "wires" for paper-making machines, which consist of a web of woven material joined together at its ends to form an endless belt or screen.

It is known in connection with paper-making machines that wires made from plastic are more resistant to abrasion than metal wires. The ends of a screen woven in web-fashion cannot be joined together to form an endless screen by welding together the adjacent synthetic filaments, because the strength of the joint obtained would be inadequate. Bonded lap points are not recommended because they impair the permeability of the screen. To obviate these disadvantages, circular looms of great dimensions have been used to produce endless screens, thus avoiding the need for joints. Unfortunately, excessive expense is involved with such looms.

Therefore, it is an object of the present invention to provide endless screens or sieves or the like woven from synthetic filaments with joints of high strength in the woven structure which have little or no effect on the permeability of the screen.

Further objects of the present invention and advantages thereof will become apparent as the following description proceeds.

The present invention provides a screen or sieve woven from synthetic filaments and, more particularly, a wire for paper-making machines, which comprises an endless web of woven material the connections between the ends of the individual warp filaments being distributed over a large area of the web and the warp filaments being connected together at their end faces pointing in the filament direction independently of the weft filaments.

According to the present invention, therefore, the connections between the individual warp filaments are distributed over a relatively large area of the web in such a way that several connections do not lie immediately adjacent each other in one row, so that instead of the usual linear joint, the warp filaments at the ends of the screen are connected together in a staggered relationship. If however there are two connections directly adjacent one another, there is still room for movement or yield towards the sides, because other connections are located further away.

Those ends of the warp filaments to be united are preferably cut at an angle with regard to the longitudinal direction of said filament and are bonded together. Since the individual connections do not lie in a row, but are distributed over a relatively large area, even a slightly

2

thicker bond would not have any appreciable effect on the permeability of the screen. In a particular embodiment of the present invention, the warp connections are alternately arranged in pairs, and not in random order, in one row at either end of the joint. Although imprints could in this case be left behind by the two rows formed by the connections, they would only appear as a dotted line at the ends of the joint.

In the attached drawing:

FIG. 1 shows in perspective an endless sieve in a paper-making machine; and

FIGS. 2 to 5 are plan views, on enlarged scales of sections from different paper machine wires or screens, embodying various possibilities of connecting the warps together to form an endless screen or sieve.

In FIG. 1 is shown an endless sieve 8 of which a part 9 is somewhat enlarged.

Each screen is woven in known manner from warp filaments A and weft filaments B made from a synthetic material. For the sake of clarity, the connections C have been shaded in the drawings.

Two rows and five rows, respectively, of warp connections C are shown at the upper and lower ends, respectively, of FIGURE 2. The warp filaments are connected together by cutting them at an angle and bonding them together. Between rows 1 and 2 there is a gap or interval of two uninterrupted mesh divisions, while the gap between rows 3 to 7 varies in size. Rows 1 and 2 are separated from rows 3 to 7 by eleven mesh divisions. The number of connections is irregularly distributed in all the rows.

FIG. 3 shows another example, incorporating four rows 1 to 4 of connections C between warp filaments cut at an angle. In this case, too, the rows in each group 1-2 and 3-4 are separated from one another by two mesh divisions, while group 1-2 is separated from group 3-4 by thirteen mesh divisions.

FIG. 4 shows a six-row arrangement of connections in which the two outer rows 1 and 6 have as many connections C as the four inner rows 2 to 5 together.

In FIG. 5, there are only two rows of connections between warp filaments cut at an angle. These two rows are separated from one another by nineteen mesh divisions. In this case, the connections are alternately formed in pairs, and not in random order, in one row 1 or 2 at either end of the joint.

Each of the examples illustrated embodies the principle of the invention, namely to form the connections between the warp filaments not in a line, as is the case with welded metal wires, but over an area with at least one uninterrupted mesh division and covering several wefts. This avoids an accumulation of bonds while the permeability of the screen as a whole remains practically uniform. By virtue of the long overlap between the warp filaments in the wide joint, the points at which they are bonded together remain largely unaffected by tensile forces because the entire woven or plaited structure carries the mesh "field." This is another important advantage of the large-area screen joint.

By virtue of the fact that, in the joining of the screen, the weft filaments in this zone are not replaced or temporarily removed, the warp filaments always fit exactly back into the "kinks" in the weft filaments, so that neither the mesh pattern nor the surface of the screen are altered at the screen joint.

To increase its strength, the entire screen is advantageously coated with a plastic solution, preferably a polyurethane composition, after the warps have been bonded together. The coating can be hardened at normal temperature or at elevated temperature. As a result, the warp and weft filaments are bonded together at their

intersections, so that the strength of the screen joint is increased and the mesh pattern is kept intact.

What we claim is:

1. An endless sieve for paper-making machines, said sieve comprising woven synthetic warp and weft filaments, in which, independently of the weft filaments, the warp filaments are connected together at end abutting faces pointing in the longitudinal direction of said warp filaments, said warp filaments and said weft filaments remaining in their original woven positions, the connections between said warp filaments being arranged in at least two separate groups each including at least one row such that the connections of the warp filaments are not all in the same row, said groups being separated from one another by at least two mesh divisions, the connections between adjacent rows in each group being spaced by at least one intact mesh division, said abutting ends being inclined at an angle with regard to the longitudinal direction of the filaments and being disposed intermediate adjacent weft filaments.

2. An endless sieve as claimed in claim 1, said sieve being provided with a hardened plastic coating.

3. An endless sieve as claimed in claim 2, wherein the plastic coating comprises a polyurethane.
